UNITED STATES PATENT OFFICE.

HENRY E. WEEKES, OF VALLEJO, CALIFORNIA.

CURTAIN-GUIDE.

1,287,539.

Specification of Letters Patent.

Patented Dec. 10, 1918.

Application filed July 11, 1918. Serial No. 244,405.

To all whom it may concern:

Be it known that I, HENRY E. WEEKES, a citizen of the United States, residing at Vallejo, in the county of Solano, State of California, have invented a new and useful Curtain-Guide; and I do hereby declare the following to be a full, clear, and exact description of the invention, such as will enable others skilled in the art to which it appertains to make and use the same.

The present invention relates to a sliding door for tents and canopies, the invention being adapted to be employed wherever a door controlled opening is desired in a flexible or fabric wall for any purpose whatever, such as for passage, light or ventilation.

Among the objects of the invention is to provide a flexible sliding closure or door which can be easily moved into a closed, open or partially open position, which will not pull away from or become separated from the edges of the door opening in the fabric wall, which is simple and inexpensive in its construction, which effectively closes the door opening when moved into a closed position, and does not in any way interfere with the making up of tent or other material as there are no rods or bars to break or bend.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:

Figure 1 is a front elevation of a portion of a fabric wall provided with a vertically movable sliding door constructed in accordance with the invention, the door being shown by full lines in a closed position and by dotted lines in a partially open position.

Fig. 2 is an enlarged side elevation of one of the guide members for the sliding door or curtain.

Fig. 3 is a longitudinal sectional view taken on the line 3—3 of Fig. 2.

Fig. 4 is an enlarged side elevation of one of the guide members, showing a slight modification.

Fig. 5 is a longitudinal sectional view on the line 5—5 of Fig. 4.

Corresponding and like parts are referred to in the following description and indicated in all the views of the drawings by the same reference characters.

Referring to the drawings, which illustrate one possible embodiment of the invention, the numeral 1 designates a portion of a canvas or fabric wall which may be a part of a tent, canopy or other inclosure. This wall is provided with a vertical door opening which has parallel side edges 2. A flexible closure 3 is provided for the door opening, said closure being integral with or joined to the canvas wall 1 at the top of the door opening, and being of such a width and length as to close the door opening when it is pulled downwardly and drawn taut, as indicated by full lines on Fig. 1.

The edges of the door opening are returned and stitched at 4, thereby providing longitudinal pockets 5 which extend the full length of the door opening and loosely receive spherical balls 6. The edges of the door 3 have similar and complementary plates 7 fitted against opposite sides thereof at suitable intervals, each pair of the plates constituting a guide member and the ends of the plates projecting beyond the edges of the door so as to receive the adjacent edge 2 of the door opening between the same. The edges of the flexible door 3 may be returned at 3^a to reinforce the same, and the plates 7 are secured to the edges of the door in any suitable manner as by means of the fastening members 8. The projecting ends of the plates 7 are provided in the inner faces thereof with complementary recesses or depressions 9 which form a socket of a suitable size to receive one of the spherical balls 6, this being indicated quite clearly by Fig. 3. Each pair of the plates 7 thus provides a guide member which engages one of the balls 6, and it will be remembered that these balls are confined within the longitudinal pockets 5 at the edges of the door opening so that they are free to move longitudinally of the door opening, but are held against movement in any other direction. The fabric walls of the pockets 5 are interposed between the spherical balls 6 and the inner faces of

100

the depressions 9 in the plates 7, so that there is a frictional engagement between the members and the door or curtain 3 will remain in an adjusted position. With this construction the edges of the door or curtain 3 are securely locked to the adjacent edges of the door opening so that it is impossible for the curtain or door to pull away from the edges of the door opening, although the 5 guide members formed by the plates 7 are movable longitudinally of the door opening and can be slipped back and forth in the necessary manner to open and close the door. This provides a very simple and effective 10 sliding door closure for a tent, canopy, or fabric wall of any kind, and while the door can be easily and quickly opened, the edges thereof are held securely to the edges of the door opening so that they cannot pull away 15 therefrom, and an effective closure is provided when the door is closed.

A slight modification is illustrated by Figs. 4 and 5, in which the balls 6 are confined within pockets 5 provided between the 20 two lines of stitching 5^c, an edge portion 1^c being provided at the side of the door opening on the outside of the outer line of stitching 4^c. The flexible door or closure 3 is of such a width that the edge portion 1^c thereof overlaps the edge portion 1^c of the door opening, thereby preventing the edges of the fabric from gaping or pulling apart when the door is closed. The plates 7^c of the guide member are secured by rivets 8^c 25 to opposite sides of the edge of the door 3, the projecting ends of the plates receiving the side of the door opening between the same and being formed with the recesses or depressions 9 which receive and interlock 30 with the ball 6, exactly as in the previous instance. One of the plates 7^c, however, is crimped at 10 to receive the edge portion of the door 3 which overlaps the edge portion 1^c of the door opening, the latter being received 35 between the projecting ends of the plates, as indicated quite clearly by Fig. 5. With this construction the door can be opened and closed without difficulty, the ball 6 sliding longitudinally in the pockets 5 as the door is manipulated, and the balls and guide members co-operating with each 40 other to prevent the door from pulling away from the sides of the door opening.

Having thus described the invention, 45 what I claim as new and desire to secure by Letters Patent, is:—

1. The combination with a fabric wall having an opening therein, and a flexible closure for the opening, an edge of the opening being provided with a longitudinally extending pocket, of a ball loose in the pocket, and a guide member applied to the closure and formed with spaced arms slidably receiving the edge of the opening and 50 engaging the ball in the pocket.

2. The combination with a fabric wall having an opening therein, a flexible closure for the opening, an edge of the opening being formed with a longitudinal pocket, of a ball loose in the pocket, and a guide member applied to the closure and formed with spaced arms receiving the edge of the opening and constructed to form a socket which loosely interlocks with the ball. 70

3. The combination with a fabric wall 75 having an opening therein, and a flexible closure for the opening, an edge of the opening being formed with a longitudinal pocket, of a ball loose in the pocket, and a guide member applied to the closure and formed with spaced plates projecting from the edge thereof and receiving the edge of the opening, said plates being constructed to provide a socket which loosely receives the ball. 80

4. The combination with a fabric wall 85 having an opening therein, and a flexible closure for the opening, the edges of the opening being folded rearwardly and fastened to provide longitudinally extending pockets, balls loose within the pockets, and 90 guide members applied to the flexible closure and formed with spaced plates which project from opposite edges thereof and receive the edges of the opening between the same, said projecting edges of the plates 95 being formed with corresponding depressions which loosely receive the before mentioned balls.

5. The combination with a fabric wall 100 having an opening therein, and a flexible closure for the opening, the edges of the opening being folded rearwardly and fastened to provide longitudinal pockets, of 105 balls loose in the pockets, and complementary plates applied to the flexible closure at opposite edges thereof, the ends of the plates extending beyond the closure and receiving the respective edges of the opening between the same, said projecting ends of the plates being formed with corresponding depressions which loosely receive the before mentioned balls. 110

6. The combination with a fabric wall having an opening therein, a flexible closure for the opening, an edge of the opening being formed with a longitudinal pocket and being overlapped by the adjacent edge of the flexible closure, a ball loose in the pocket, and a guide member applied to the closure and formed of spaced arms receiving 115 the edge of the opening and constructed to form a socket which loosely interlocks with the ball, one of said arms being formed with a crimped portion receiving an overlapping edge of the fabric. 125

7. The combination with a fabric wall having an opening therein, a flexible closure for the opening, an edge portion of the opening being formed with a longitudinal pocket and the flexible closure overlapping 130

the said edge portion of the opening, of a ball loose in the pocket, and spaced plates applied to opposite sides of the flexible closure and projecting from the edge thereof, the projecting portions of the plates receiving the edge of the opening and being formed with complementary recesses providing a socket which loosely interlocks with the ball, one of said plates being provided

with a crimped portion receiving an over-lapping edge of the fabric.

In testimony whereof I have signed my name to this specification in the presence of two subscribing witnesses.
